(57) **CLAIM**

The ornamental design for battery charger for tape printing machine, as shown and described.

DESCRIPTION

FIG. 1 is a front view of a battery charger for tape printing machine;

FIG. 2 is a top view thereof;

FIG. 3 is a left-side view thereof;

FIG. 4 is a right-side view thereof;

FIG. 5 is a rear view thereof;

FIG. 6 is a bottom view thereof;

FIG. 7 is a top perspective view thereof; and,

FIG. 8 is a bottom perspective view thereof.
